UNITED STATES PATENT OFFICE.

JOHN C. SCHMIDT, OF CHICAGO, ILLINOIS.

DOOR-CHECK.

1,339,479.

Specification of Letters Patent.

Patented May 11, 1920.

Application filed May 9, 1919. Serial No. 295,934.

To all whom it may concern:

Be it known that I, JOHN C. SCHMIDT, a citizen of the United States, and resident of Chicago, in the county of Cook and State 5 of Illinois, have invented certain new and useful Improvements in Door-Checks, of which the following is a specification.

My invention relates to door checks and closers and particularly to a novel liquidless door check similar in type to that shown 10 in my prior Patent No. 1,266,864, of May 21, 1918.

One of the principal objects of the present invention is to provide a construction in 15 which the fluid employed constitutes the sole checking means as distinguished from the construction of my patent heretofore referred to in which the fluid is an auxiliary to a brake which constitutes the primary 20 checking device. One of the principal objections to the employment of air checks has been that the movement of the door toward closing position under the action of a closing spring could not be made uniform, this 25 for the very obvious reason that air being a highly compressible medium could not be caused to offer sufficient resistance to the door during the initial travel of the air compressing piston. Particularly is this true 30 as the closing spring exerts its greatest power when the door is opened, this power being exerted during the initial portion of the closing movement.

I have conceived the idea that the closing movement of the door may be made uniform throughout by employing two cylinders and pistons, one of which acts to compress the air and the other to rarefy it. It is well known that vacuum offers high 35 resistance in a properly constructed cylinder and piston, but that upon the admission of a small quantity of air the vacuum is rapidly dissipated, and, as in my device the vacuum resistance takes effect at the point where the 40 spring is exerting its greatest force it conforms strictly to the necessity of the case. As the pistons travel, however, the pressure 45 is built up in the opposite cylinder and by the time the vacuum cylinder is offering but little resistance the compression cylinder 50 will begin to take effect and as the change from one to the other is gradual the door closing movement may be made uniform.

The invention will be more readily under-

stood by reference to the accompanying 55 drawings, wherein,

Figure 1 is a longitudinal sectional view through a device constructed in accordance with my invention, the view being taken on the line 1—1 of Fig. 2, and 60

Fig. 2 is a sectional view on the line 2—2 of Fig. 1.

In the drawings it will be seen that I provide a casing 10 having attaching flanges 11 and carrying in one portion thereof a container or housing for a door-closing coil spring 12. Centrally mounted within the casing is a winding sleeve 13 which carries the shaft 14 to which the door operating arm 15 is secured. At the lower end the 70 shaft has rigidly secured thereto an arm 16 which is connected by links or pitmen 17, 18, to pistons 19, 20. The pistons are adapted to reciprocate within cylinders 21, 22, which in the form shown are secured to 75 the casing 10 by screw threads. The outer ends of the cylinders are closed by caps 23, 24, having air control valves 25, 26 therein. The parts are shown in a position such as would be assumed when the door is in closed 80 position. On the opening movement the pistons 19, 20, will move to opposite positions, the arm 16 traveling through 160°. The extent of vacuum and compression will, of course, be controlled by adjustment of the 85 valves 25, 26. It will be noted that these do not function as check valves, but are permanently held in adjusted position. Provided within the pistons 19, 20 are check valves 27, 28, identically disposed with relation to 90 the travel of the pistons. A movement of the pistons to the left as viewed in Fig. 1—that is the movement produced by the opening of the door to which the check is connected—is free as to both pistons, due to the 95 position of the check valves. On the return movement, however, no air can pass through pistons, the only change in quantity of air being effected by passage through the restricted apertures controlled by the valves 100 25, 26.

The closing movement of the door will be uniformly resisted because of the fact that at the beginning of the closing movement there will be created a high degree of vacuum within the cylinder 21. However, as the travel increases this resistance will be reduced as air is admitted through the con-

trol valve 25. At the same time the compression in the opposite cylinder will progressively increase and will, in fact, be much higher than atmospheric pressure as the door reaches its closed position. There has heretofore been no difficulty in controlling the final portion of the closing movement, the difficulty having been in restraining the door during the initial portion of the movement and to avoid so great a speed that when a suitable pressure has been attained, the door would rebound due to the resilient medium under compression. By the use of the device herein disclosed there is no lack of uniformity in the movement of the door and difficulties heretofore encountered will be avoided. This result is secured because the highest degree of vacuum is secured during the initial portion of the stroke or movement of the piston and the degree of vacuum is progressively reduced in the ratio which any specified movement of the piston bears to the total preceding movement. In the opposed cylinder, however, the reverse is true as the compression is increased according to the same law. The mechanism described is only necessary where a compressible medium is utilized, the same problems are not present nor can the same mechanism be used where a liquid is employed.

It will be understood that the principle of employing compression and vacuum might be utilized in a single cylinder and a single piston, the opposite sides of the piston performing the desired functions. This and other modifications, such as will readily suggest themselves to those skilled in the art, are considered to be within the spirit of my invention.

40 I claim:

1. In a pneumatic checking device, the combination of a shaft through which the checking effort is transmitted, a pair of cylinders, pistons in said cylinders, means for

transmitting the movement of the pistons to the shaft to rotate the same, said pistons being mounted for travel in unison toward opposite ends of said cylinders, means providing a permanently open, regulably restricted passage between the atmosphere and the interior of each cylinder, and valves permitting unrestricted movement of said pistons in one direction, substantially as described.

2. In a pneumatic checking device, the combination of a shaft through which the checking effort is transmitted, a pair of cylinders, pistons in said cylinders, a crank on said shaft, pitmen connecting the crank to said pistons, said pistons being so arranged with relation to said crank that in an extreme position they occupy opposite ends of their respective cylinders, valves permitting unrestricted movement of the pistons in one direction, and means providing a permanently open, regulably restricted passage in the otherwise closed end of each cylinder, substantially as described.

3. In a pneumatic checking device, the combination of a shaft through which the checking effort is transmitted, a pair of cylinders, pistons in said cylinders, a crank on said shaft, pitmen connecting the crank to said pistons, said pistons being so arranged with relation to said crank that in an extreme position they occupy opposite ends of their respective cylinders, valves permitting unrestricted movement of the pistons in one direction, and means providing a permanently open, regulably restricted passage between the atmosphere and the interior of each cylinder, substantially as described.

Signed at Chicago, Illinois, this 6th day of May, 1919.

JOHN C. SCHMIDT.
